UNITED STATES PATENT OFFICE.

HARRY P. MAHONEY, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed November 25, 1922. Serial No. 603,155.

My invention relates in general to telephone systems in which connections may be established through the medium of subscriber controlled selector and connector switches, or in which an operator is depended upon to manually interconnect the subscribers' circuits for purposes of conversation; but is more particularly concerned with the transmission of fire, burglar, or other alarm signals; and the object of the invention may be said to be, broadly, the provision of new and improved auxiliary apparatus for use in connection with a telephone system.

It is sometimes desirable to associate an auxiliary service of some type with a telephone system, so as to utilize the telephone lines and other apparatus of the telephone system for the auxiliary service. As is well known, the ordinary telephone lines of an exchange are idle a great part of the day and practically all of the night, and a large proportion of the capital invested in the telephone plant is therefore idle and incapable of earning revenue; but by combining an auxiliary service with the telephone service an additional earning capacity is thus imparted to the capital invested in the plant.

In the preferred embodiment of my invention I employ in connection with a common battery telephone exchange means by which a subscriber, when desiring protection, may cause a high resistance to be connected between the negative side of the telephone line and ground at his substation. This resistance thereupon allows sufficient current to flow to preserve the normal condition of the alarm receiving apparatus. The alarm receiving apparatus consists, in part, of two relays connected in series, and in circuit with the high resistance at the substation. One relay being comparatively high in resistance is designed to be continuously operated when in circuit with the above mentioned resistance. The second relay being low in resistance does not operate when in circuit with the above mentioned resistance, but is so designed that it will operate should the said resistance become short circuited.

It is thus seen that my invention comprises the combination of a normal telephone circuit with an alarm circuit, in which there is a comparatively weak but continuous current flow during the time that a

given substation is under protection, this current flow serving to preserve the normal condition of the alarm receiving apparatus. When this current is interrupted as the result, for instance, of the opening of a door, the breaking of a window or the operation of a fusible link, the comparatively high resistance relay in the alarm receiving apparatus will deenergize and thus bring in the alarm. If, in an attempt to outwit the alarm system, the high resistance at the substation becomes short circuited the increased current flow will be such as to operate the low resistance relay in the alarm receiving apparatus, thus bringing in the alarm.

Referring to the drawings, Figs. 1 and 2 are circuit diagrams of sufficient of the apparatus to illustrate the preferred form of the invention, Fig. 1 discloses the equipment pertaining to an automatic telephone switchboard wherewith to establish a connection between a calling substation A and a called substation A', while Fig. 2 shows the auxiliary alarm equipment. In view of the fact that much of the telephone apparatus is well known the detailed circuits have in some instances been omitted and the apparatus merely indicated in schematic form. The line circuits, however, have been shown complete.

The apparatus shown may be briefly described as follows: The substation A is an automatic substation or telephone of well known type. In close proximity thereto is mounted the locking key K, this being the key which is operated when the subscriber desires protection. It is to be assumed that the watchman's jack J is mounted in a secret place outside the premises, its location being known only to the patrolman on the beat. The substation is connected with the central office by the line comprising conductors 11 and 12. At the exchange this line terminates in the individual line or trunk selecting switch indicated by the reference character C. This individual switch is of a well known type, the only change being in the manner in which positive and negative battery is normally fed to the line. The line switch C has access in the usual manner to a plurality of first selectors, such as the selector E. The first selectors have access in the usual manner to a plurality of second selector switches, such as the selector E'. The

second selectors have access in the usual manner to a plurality of connectors, such as the connector H. The connectors in turn having access to a plurality of line switches, 5 such as the line switch C', which is similar to the line switch C. The equipment associated with the substation A' may be considered to be the same as that associated with substation A.

10 In Fig. 2 is shown, in part, the equipment mounted upon the alarm board. This equipment will consist of a locking key K², a guard lamp L, an alarm lamp L' and a multiple line jack J², for each line which is to be given protection. A cord circuit B is provided in order that the attendant may supervise a line under protection. Adjacent to each line jack, such as the jack J², will be placed a designation strip showing the 15 number of the associated telephone line and the hours during which this line is to be under protection. For instance, the designation might be as follows: "Telephone No. 2829. Protect from 5:30 p. m. to 9:00 20 a. m.—K.Y.W."

It is thought that the operation of the auxiliary apparatus can best be explained by first describing the operations which take place when the subscriber at substation A 25 calls the subscriber at substation A'. When the receiver at substation A is removed a circuit is closed through the line relay 13 of line switch C. This circuit may be traced from ground G at the line switch C, through 30 the line relay 13, through the cut off springs 14 and 15, line conductor 12, through the substation A, line conductor 11, through the cut off springs 17 and 18, through the low resistance relay 20, through the comparatively high resistance relay 21, to negative battery. The relays 20 and 21 will energize over this circuit, but their operation at this 35 time is without effect. The line relay 13 will energize over the above traced circuit and will close a circuit through the operating winding 22 of the line switch C, whereupon the line switch C is operated in the usual manner to extend the connection to an idle first selector switch. As is well 40 known, the cut off springs are now in an operated position, thus removing relays 13, 20 and 21 from the calling line. Successive operations of the dial now cause the operation of the selected first selector, a 45 second selector and a connector. Let us assume that the called line is idle, and that the connector has caused the cut off relay 23 of the line switch C' to become operated. The operation of the cut off relay 23 resulted 50 in the removal of relays 24, 25 and 26 from the called line. The called substation is now being signalled, and when the called party answers, conversation may proceed as desired. When the subscribers are through 55 they will both replace their receivers, where-

upon the release of the apparatus will take place in the usual manner. The relays 13, 20 and 21 will again be connected to the calling line, while relays 24, 25 and 26 will again be connected to the called line.

The auxiliary service which I show in connection with this invention is for fire, burglar or other alarm service and will now be explained in detail. We may assume that the substation A shown on the drawing is 70 the substation referred to by the following designation on the alarm board, "Telephone No. 2829. Protect from 5:30 p. m. to 9:00 a. m. K. Y. W." The subscriber at substation A will operate the locking key K sometime previous to 5:30 p. m. When this key is operated the comparatively high resistance relay 21 at the central office will become energized over a circuit which may be traced from ground G² at the calling substation, through the adjustable resistance 75 27, through a series of conductors represented by the figure 28, through the locking key K, conductor 11, through cut off springs 17 and 18, through the low resistance relay 20, through the comparatively high resistance relay 21, to negative battery. The comparatively high resistance relay 21 will energize over the above traced circuit, but is without effect at this time. The resistance 80 27 is so adjusted that the low resistance relay 20 will not operate when in series with it.

Promptly at 5:30 p. m. the attendant will go over the alarm board and operate the locking key associated with each line that is to go under protection at 5:30 p. m. When the key K² is operated the guard lamp L will light as an indication that the key K at the associated substation has been operated, and that the line is now under protection. The circuit may be traced from ground G³, through locking key K², springs 29 and 30, through guard lamp L, to negative battery. Promptly at 9:00 a. m. the attendant will go over the alarm board and restore the locking key associated with each line that is to go off protection at that hour. When the key K² is restored the lamp L will be extinguished, indicating that the associated line is no longer under protection. 105 The subscriber, entering his place of business sometime after 9:00 a. m., will restore key K, thus causing the deenergization of relay 21. The auxiliary apparatus is now 110 at normal and will remain so until the line again goes under protection at 5:30 p. m. 115

The operation resulting from the opening of one of the conductors represented by the reference figure 28 will now be explained, it being assumed that the substation A is 120 under protection. It is to be understood that the conductors represented by the figure 28 may vary in number depending upon local requirements; and that these conductors may consist of a pair of contacts de- 125 130

signed to be separated by the opening of a door or window; a fragile conductor designed to be opened by the breaking of a pane of glass; a conductor designed to fuse and open the circuit at a predetermined temperature; a combination of the above, or in fact, any device known to the art whereby a closed circuit alarm system may be opened. As may be seen from the circuit, the opening of any conductor in the series will cause the deenergization of the moderately high resistance relay 21, as a result of which the alarm lamp L' will light. The circuit may be traced from ground G³, through key K², through springs 29 and 31, through alarm lamp L', through pilot relay 32, to negative battery. The pilot relay will energize over this circuit and bring in both a visual and an audible alarm. The attendant, seeing the lamp L' lighted, will insert the plug P into the jack J². The secondary and tertiary windings of the induction coil, in series with the operator's head set, are now bridged across line conductors 11 and 12. This is a standard monitoring circuit and allows the operator to listen in on the line. The operator then depresses the locking key K⁴, which causes the cut off relay 33 of the line switch C to operate, thereby removing relays 13, 20 and 21 from the line. As the line is now clear at the line switch C the operator may depress the key K⁶ and connect the line to a testing circuit. After completing the test the operator will dispatch a patrolman to the premises to make an investigation.

The operation resulting from an attempt to outwit the alarm system by grounding the line conductor 11 will now be explained, it being assumed that the substation A is under protection. When conductor 11 is grounded, as at G⁴, the low resistance relay 20 will energize and cause the alarm lamp L' to light. The circuit may be traced from ground at G⁴, over line conductor 11, through cut off springs 17 and 18, through the low resistance relay 20, through the moderately high resistance relay 21, to negative battery. The increased circuit flow will of course have no effect upon relay 21, as that relay is already in an operated position. The increased circuit flow will, however, cause the low resistance relay 20 to operate, and as a result the alarm lamp L' will be lighted. The circuit may be traced from ground G³, through locking key K², through springs 34 and 35, through the alarm lamp L', through pilot relay 32, to negative battery. The pilot relay will energize over this circuit and bring in both a visual and an audible alarm. The attendant seeing the lamp L' lighted will insert the plug P into the jack J², the procedure being the same as explained in the preceding paragraph.

65 The operation resulting from an attempt

to make a telephone call at a station under protection will now be explained, it being assumed that substation A is under protection. The preferred operation would be that in which the subscriber first restored the key K, after which he would remove the telephone receiver and make the call in the usual manner. It would be entirely possible for the subscriber to remove the receiver and make the call without restoring the key K, in this case, however, the resistance 27 would be bridged between line conductor 11 and ground. In either event the moderately high resistance relay 21 would deenergize; in the first case because of the opening of its circuit at key K, in the second case because of the opening of its circuit at the cut off springs 17 and 18. The deenergization of the relay 21 will cause the alarm lamp L' to light and attract the attention of the attendant in the usual manner. The attendant thereupon inserts the plug P in the jack J². As previously explained, the cord circuit B is normally a monitoring circuit, which allows the attendant to listen in on the connection without interfering with the dialling or otherwise affecting the telephone connection. The attendant will now depress the key K⁵ which closes the primary circuit of the induction coil, removes the tertiary winding, and in fact changes the cord circuit B into a standard operator's talking circuit. The operator will now challenge the calling party, and if the password "K. Y. W." is given, the attendant may assume that the call is a legitimate one being made by the subscriber at substation A, the password for each station being the code shown upon the designation strip, associated with the line in question, at the alarm board. If the calling party cannot give the password the attendant will send a patrolman to make an investigation of the premises. If the call is a legitimate one the attendant will remove the plug P from the jack J², the connection being supervised by the alarm lamp L' which will remain lighted until the calling subscriber restores his receiver to the switchhook and again depresses the key K.

The operation in connection with the watchman's jack J will now be explained, it being assumed that the substation A is under protection. The patrolman on the beat will call in at stated intervals by inserting the plug associated with his hand telephone into the secret watchman's jack mounted outside the premises of the subscriber. When the patrolman inserts a plug into the jack J the associated line switch C will operate in the usual manner, thereby opening the circuit of relay 21 at springs 17 and 18. As a result the alarm lamp L' will light and the attendant will plug in on the connection and talk to the patrolman.

It is to be noted that the jack J is connected to the line only when the key K is in an operating position, and therefore, the watchman's jack is operative only when the 5 substation is under protection.

The operation required when a line under protection is called from another telephone will now be explained, it being assumed that the substation A' is under protection. When 10 substation A' is called the connector H will cause the operation of the cut off relay 23 of the line switch C', and as a result relay 25 will deenergize and cause the alarm lamp L³ to light. The attendant thereupon will place 15 the plug P in the jack J³, operating the key K⁵ to cut off the ring and to allow him to talk to the calling subscriber. The attendant will give the calling subscriber such information as may be desired and, if the calling 20 subscriber does not release promptly, the alarm board attendant will get in touch with the switchboard attendant and request him to take down the connection standing on the line to which substation A' is connected. 25 This provision is made in order that a calling subscriber cannot innocently or maliciously render inoperative the alarm service of a called line.

The apparatus represented in Fig. 2 may be, 30 and preferably is, located in a separate room from the switchboard at the exchange and is looked after by an entirely different set of attendants. In other words, the alarm apparatus may be separate and distinct and handled separately from the telephone exchange 35 apparatus. This method of interpolating auxiliary apparatus in telephone lines is very readily accomplished in either existing or contemplated exchanges without deviation 40 from established practice in their installation and operation.

It is evident that one skilled in the art may utilize my invention in other systems than that shown without departing from its spirit, 45 and I therefore do not wish to limit myself to the specific structure illustrated and described.

The object and scope of the invention having 50 been described, what is considered to be new and what it is desired to have protected by Letters Patent will be pointed out more specifically in the appended claims.

What I claim is:

1. In an alarm system, a closed circuit connecting a subscriber's premises with a central station, a resistance and a plurality of conductors included in said circuit at the subscriber's premises, said conductors adapted to be broken by any agency against which the alarm is provided, a normally energized relay in said circuit at said station adapted to deenergize if one of said conductors is broken, a normally deenergized relay in said 60 circuit in series with said first relay and adapted to energize if said resistance is short 65

circuited, and an alarm operated by the de-energization of said first relay or the energization of said second relay.

2. In a combined telephone and alarm system, a subscriber's telephone line, means for 70 extending connections to or from said line to include said line in talking circuits with other subscribers' lines, an alarm circuit superimposed on said first line including protective devices, an alarm at the exchange, and responsive devices for actuating said alarm in case said circuit is altered at the subscriber's station and whenever said line is calling or is being called. 75

3. In a combined telephone and alarm system, a subscriber's telephone line, means for 80 extending connections to or from said line to include said line in talking circuits with other subscribers' lines, an alarm circuit superimposed on said first line, a normally 85 energized relay at the exchange included in said circuit and adapted to deenergize if the circuit is broken at the subscriber's station, an alarm operated when said relay is deenergized, and a cut off relay for opening said 90 circuit whenever said first line is calling or is being called.

4. In a combined telephone and alarm system, a subscriber's telephone line, means for 95 extending connections to or from said line to include said line in talking circuits with other subscribers' lines, a normally inoperative alarm system including a circuit superimposed on said line, and manually 100 operable devices at the subscriber's station and at the exchange co-operating to render the alarm system operative to protect the subscriber's premises, said manually operable device at the station closing said circuit continuously. 105

5. In a combined telephone and alarm system, a subscriber's telephone line, means for 110 extending connections to or from said line to include said line in talking circuits with other subscribers' lines, an alarm circuit superimposed on said line and normally 115 open at the subscriber's end thereof, a local alarm circuit at the exchange also normally open, and devices at the subscriber's station and at the exchange, respectively, for closing said circuits at a prearranged time without operating the alarm in order to place the subscriber's premises under protection, and means for thereafter operating said alarm. 120

6. In a combined telephone and alarm system, a subscriber's telephone line, means for 125 extending connections to or from said line, a normally inoperative alarm circuit superimposed on said line, manually operable devices on the line at the subscriber's station and at the exchange co-operating to render the alarm system operative, and additional devices in said circuit at the subscriber's station for controlling said circuit to operate an 130 alarm.

7. In a combined telephone and alarm system, a subscriber's telephone line, means for extending connections to or from said line to include said line in talking circuits with other subscribers' lines, an alarm circuit superimposed on only one side of said first line, an alarm at the exchange, and devices responsive to a call to or from said first line and responsive to an alteration of the circuit of said line to actuate said alarm.
8. In a combined telephone and alarm system, a subscriber's line circuit, talking instrumentalities on said line and means for connecting them in circuit with the line, an auxiliary circuit including said subscriber's line and alarm devices at the exchange, means for rendering said circuit effective, a signal at the exchange to indicate that the auxiliary circuit has been rendered effective, and means at the substation for operating an alarm at the exchange over said circuit.
9. In a combined telephone and alarm system, a subscriber's line, means for extending connections to or from said line, an auxiliary alarm circuit including said line and signalling devices at the exchange, means at

the station on the line for rendering said auxiliary circuit effective, means at the substation for operating an alarm at the exchange over said circuit, and means at the exchange for operating an alarm over said circuit when a call is made to or from said line.

10. In a combined telephone and alarm system, a subscriber's telephone line, means for extending connections to or from said line to include said line in talking circuits with other subscriber's lines, an alarm circuit superimposed on only one side of said first line, an alarm at the exchange, manually operable devices on the line at said subscriber's station and at the exchange, cooperating to render the alarm system operative, and devices responsive to a call to or from said line and responsive to an alteration of the circuit at the subscriber's station to actuate said alarm after the said manually operable devices have been operated.

In witness whereof, I hereunto subscribe by name this 20th day of November, A. D. 1922.

HARRY P. MAHONEY.
